UNITED STATES PATENT OFFICE.

PHILIP C. P. BOOTY, OF CHICAGO, ILLINOIS, ASSIGNOR TO MICHAEL T. DALEY, OF CHICAGO, ILLINOIS.

RECEPTACLE FOR FACE POWDER AND THE LIKE.

Application filed October 13, 1926, Serial No. 141,288, and in Canada January 27, 1926.

My invention relates to receptacles for holding and dispensing face powder and the like in loose form and particularly to a form of device such as that shown in my prior application, Serial No. 10,736, filed February 21, 1925, of which this application is a continuation in part.

It is one of the objects of my present invention to provide in a device of this type a new and improved form and arrangement of parts for filling the receptacle whereby the operation of inserting the powder into the box and the operation of ejecting the powder therefrom in the desired small quantities may be performed to advantage, while at the same time ample provision is made for preventing accidental leakage of the powder from the box under any ordinary conditions of use.

To this end, it is one of the objects of my invention to provide a construction in which an outwardly convex closure plate is used for closing the opening through which the powder is normally inserted into the box, such closure plate being adapted to extend outwardly slightly beyond the seat against which it closes, whereby a light pressure can very readily be applied thereto manually for displacing it from closing position without having the fingers actually enter the opening and whereby the powder may be very readily cleared from the top face of the closure plate without the necessity for tipping the box.

It is another object of my invention to provide in a box of this type a measure of protection against accidental application of pressure to the closure plate, such protection being afforded by reason of the fact that the portion of the casing in which the opening is provided is dished so that the opening is inset slightly with respect to the adjacent portions of the casing.

It is another object of my invention to provide a new and attractive construction of box involving a filling opening in the top face of the casing. It is still another object of my invention to improve devices of this type in sundry details hereinafter pointed out. The preferred means by which I have accomplished my several objects are illustrated in the accompanying drawing and are herein-after specifically described. That which I believe to be new and desire to cover by this application is set forth in the claims.

In the drawing—

Fig. 1 is a top plan view of the body of the preferred form of my improved device with the principal portion of the cover broken away for clearness of illustration.

Fig. 2 is a central vertical section through the box of Fig. 1.

Fig. 3 is a view similar to Fig. 2 but with the cover opened and partly broken away and showing a changed position of the parts such as is brought about in the operation of the device for ejecting the powder.

Fig. 4 is a view similar to Fig. 3 but showing another changed position of the parts such as is brought about for filling the box;

Fig. 5 is a view similar to Fig. 2 but showing a modified form of construction.

Referring particularly to Figs. 1 to 4 in which corresponding parts are indicated by the same reference characters,—10 indicates a casing formed of sheet metal and having a cover 11 pivotly mounted thereon by the use of a hinge 12. In the construction shown, the cover 11 is provided with a flange 13 which has a working fit upon the reduced upper edge portion of the casing 10. Within the flange 13 in the construction illustrated, there is mounted a mirror 14 held in position by a ring 15.

As best shown in Fig. 3, the upper edge of the sheet metal forming the casing 10 is turned inwardly and downwardly in the form of an annular flange 16. Below the flange 16 I have provided a closure plate 17 which is normally pressed upwardly into position for closing the opening defined by the flange 16 by means of a volute spring 18 which is interposed between the plate 17 and the bottom face of the casing 10. The closure plate 17 is of such a size as to have free movement within the casing 10 but such as to be held from moving laterally out of engagement with the inner edge of the flange 16. The casing 10 and closure plate 17 are arranged so as to be substantially air tight when the closure plate is in its uppermost operative position. When the plate 17 is moved rapidly up and down, a small supply of face powder contained in the casing is forced by pneumatic action about the edge of the closure plate and underneath the flange 16 into contact with the compact in position upon the closure plate, such compact being shown in the dotted lines in Fig. 3 and being indicated by the numeral 19. Inasmuch as this con-

struction is shown and claimed in parent application 10,736 above referred to, it is believed to be unnecessary to describe the same further in detail herein.

5 For filling the casing 10, I have provided an opening 20 in central position through the closure plate 17, the portion of the plate 17 adjacent to the opening 20 being dished inwardly as indicated at 21. For closing the 10 opening 20 I have provided an outwardly convex plate 22 which is held in position for closing the opening by means of a coiled spring 23 interposed between the plate 22 and the bottom face of the casing. As will be 15 readily understood, the spring 23 serves to press both the plate 22 and the plate 17 upwardly into closing position, it being evident that a heavy spring 23 would suffice without providing a spring 18. I prefer, however, to 20 provide the two springs for holding the plates in position independently of each other.

When it is desired to fill the casing 10, this can be accomplished by pressing the plate 22 downwardly with respect to the plate 17 25 against the action of the spring 23 into the position as shown in Fig. 4 whereupon a supply of powder can readily be poured into the box about the plate 22, the powder being adapted very readily to find its way into the 30 casing by reason of the dished formation of the plate 17 at 21 and by reason of the convex form of the plate 22. When the desired supply of powder has been inserted, the spring 23 serves to raise the plate 22 into closing 35 position as soon as the pressure thereon has been released, and in the operation of the device normally for ejecting the powder about the edge of the plate 17 the plates 17 and 22 serve together as the ejecting means just as 40 a single integral plate would serve. By reason of the curved formation of the plate 22, it is immaterial at what position the plate 22 stands since it is adapted to close the opening 20 in any adjusted position it is likely to 45 assume.

In the construction shown in Fig. 5, a casing 24 is provided in the form of an insert for any standard casing such as the casing 25 having a hinged cover 26. The casing 24 is 50 in general similar to the casing 10. The top face of the casing, however, is provided by a separately formed flange provided by the use of a ring 27 pressed into the upper end of the casing 24. A closure plate 28 is provided 55 being dished downwardly with respect to the opening through the ring 27 substantially throughout the entire diameter of the plate. The construction in other respects is similar to that above described except that the spring 60 23 in the construction shown is secured by means of solder to both the closure plate 22 and the bottom face of the casing 24, and that the spring 18 is secured by solder to the bottom face of the casing 24. Inasmuch as the operation 65 of the device of Fig. 5 is the same as

that above described, it is believed to be unnecessary to describe the same further herein. The only difference is that the action of the parts is made a little more positive by reason of the solder connection of the springs and that the filling operation in connection with the structure of Fig. 5 might be slightly facilitated by reason of the increased dishing of the plate 28. In the use of either of the constructions, the outwardly convexed plate 22 is very readily pushed downward for filling the box by reason of the fact that the plate extends upwardly beyond the adjacent portions of the upper face of the main closure plate. The plate 22, however, does not extend above the outer edge of the casing and does not extend above the outer edge of the main closure plate, the upstanding outer parts serving to protect the plate 22 from accidental downward displacement by reason of pressure applied generally upon the upper face of the casing.

While I prefer to employ a construction such as that shown in my drawing, it will be understood that I do not wish to restrict my invention to the form shown except so far as certain of the claims may be specifically so limited, since it will be seen that changes might well be made in the construction without departing from the spirit of my invention.

I claim—

1. A receptacle for face powder and the like, comprising in combination a casing having an opening in its top face, an outwardly convex closure plate within the casing fitted to said opening, and yielding means for pressing said closure plate upwardly into position for closing said opening. 100

2. A receptacle for face powder and the like, comprising in combination a casing having an inwardly dished top face portion with an opening in the depression thereof, an outwardly convex closure plate within the casing fitted to said opening, and yielding means for pressing said closure plate upwardly into position for closing said opening. 105

3. A receptacle for face powder and the like, comprising in combination a casing having an opening in its top face, a closure plate underlying the opening, a volute spring engaging said plate at points adjacent to the margin of the opening for pressing the plate into position for closing the opening, and a second spring inside of the first named spring serving to assist in holding the closure plate yieldingly in closing position. 115

4. A receptacle for face powder and the like comprising in combination a casing having an opening in its top face, a closure plate underlying the opening, a spring serving to press said closure plate into position for closing said opening, a second opening in said closure plate for filling the casing, and means for closing said second opening. 125 130

5. A receptacle for face powder and the like, comprising in combination a casing having an opening in its top face, a closure plate underlying the opening, a spring serving to 5 press said closure plate yieldingly into position for closing said opening, a second opening in said closure plate for filling the casing, a second closure plate underlying said second opening, and a second spring serving to press 10 said second closure plate yieldingly into position for closing said second opening.
6. A receptacle for face powder and the like, comprising in combination a casing having an opening in its top face, a closure plate 15 underlying the opening, a spring serving to press said closure plate yieldingly into position for closing said opening, a second opening in said closure plate for filling the casing, a second closure plate of outwardly con- 20 vex form underlying said second opening and extending slightly therethrough, and a second spring serving to press said second closure plate yieldingly into position for closing said second opening.
- 25 7. A receptacle for face powder and the like, comprising in combination a casing having an opening in its top face, a downwardly dished closure plate underlying said opening, a spring serving to press said closure plate 30 yieldingly into position for closing said opening, a second opening through the depressed dished portion of the plate, a second closure plate underlying said second opening, and a
- second spring serving to press said second closure plate yieldingly into position for closing said second opening. 35
8. A receptacle for face powder and the like, comprising in combination a casing having an opening in its top face, a downwardly dished closure plate underlying said opening, a spring serving to press said closure plate 40 yieldingly into position for closing said opening, a second opening through the depressed dished portion of the plate, a second closure plate of outwardly convex form underlying 45 said second opening and extending slightly therethrough, and a second spring serving to press said second closure plate yieldingly into position for closing said second opening.
9. A receptacle for face powder and the like, comprising in combination a casing having an opening in its top face, a downwardly dished closure plate underlying said opening, a spring serving to press said closure plate 50 yieldingly into position for closing said opening, a second opening through the depressed dished portion of the plate, a second closure plate of outwardly convex form underlying 55 said second opening and extending ther- 60 through to a level below that of the outer portion of the first named closure plate, and a second spring serving to press said second closure plate yieldingly into position for closing said second opening.

PHILIP C. P. BOOTY.
